UNITED STATES PATENT OFFICE

155,336

DESIGN FOR A WEATHER GLASS

William F. Downes, Bridgeport, Conn.

Application May 6, 1948, Serial No. 146,202

Term of patent 14 years

(Cl. D52—7)

To all whom it may concern:

Be it known that I, William F. Downes, a citizen of the United States, residing at Bridgeport, county of Fairfield, and State of Connecticut, have invented a new, original, and ornamental Design for a Weather Glass, of which the following is a specification, reference being had to the accompanying drawing, forming part thereof.

Figure 1 is a side view of a weather glass, showing my new design.

Fig. 2 is a front view of the same.

Fig. 3 is a rear view of the same.

I claim:

The ornamental design for a weather glass, as shown.

WILLIAM F. DOWNES.
